ELECTRIC IRON STAND

William Edelman, Bronx, N. Y.

Application October 19, 1934, Serial No. 748,983

8 Claims. (Cl. 219—25)

This invention relates to new and useful improvements in a sad iron stand.

The invention has for an object the construction of a stand for a sad iron which is characterized by the provision of a horizontal sad iron support wall, pointed at the front and straight at the rear, and provided with a surrounding flange having cam projections arranged in such a manner that when the sad iron is placed casually on the stand it will automatically slip into proper position on the horizontal wall.

More particularly, the invention proposes the arrangement of the flanges so as to have raised portions at the point of the horizontal support wall, which raised portions act to automatically cause the iron to slide into proper position.

Still further the invention also proposes a provision wherein a pair of spaced overhanging lugs project from a casing having said horizontal sad iron support wall, and an insulation block mounted across the bottoms of said spaced lugs in a novel fashion for supporting contacting mechanisms for the automatic closing of an electric circuit through the sad iron when the iron is placed in position on the stand.

Still further the invention contemplates the association of a switch upon the casing of the stand, and electrically connected with the contacts upon the insulation block, to control the operation of the iron.

Another one of the objects of this invention is the arrangement of the insulation block in such a manner that it may be shifted from one into another position so as to shift the positions of the contacts, providing for the location of the contacts in a position in which the sad iron may assume its natural position on the stand without closing the electrical circuit.

Still further the invention proposes the construction of a device as mentioned which is simple and durable and which can be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a plan view of a sad iron and stand according to this invention, with certain outer parts removed to disclose interior parts.

Fig. 2 is a side elevational view of Fig. 1.

Fig. 3 is a perspective view of the stand per se, with certain portions removed.

Fig. 4 is a sectional view as if taken on the line 4—4 of Fig. 1.

Fig. 5 is a sectional view taken on the line 5—5 of Fig. 1.

Fig. 6 is a plan view of the sad iron, per se.

Fig. 7 is an enlarged sectional view taken on the line 7—7 of Fig. 1.

The sad iron stand, according to this invention, 10 comprises a casing having a horizontal sad iron support wall 10 with a pointed front 10^a and a straight rear 10^b. A flange 11 surrounds the sides and the pointed front of the wall 10. Cam projections 11^a are arranged upon the flange 11 15 at the point area thereof and are adapted to cause the proper seating of the sad iron on the stand when the iron is casually placed in position. A pair of spaced overhanging lugs 12 project from the rear of the said casing. 20

An insulation block 13 is attached across the bottoms of the lugs 12. Resiliently supported contacts 14 are mounted upon the insulation block 13. The contacts 14 normally depend and are adapted to be automatically raised by co- 25 acting contacts 15 mounted upon a tail portion of the sad iron as hereinafter described. The flanges 11 of the sad iron stand extend below the horizontal wall 10 as clearly illustrated in Figs. 2 and 4, so that the stand rests merely upon the 30 flanges on some support. There is therefore an insulating area 16 beneath the stand to air insulate the support from the full force of heat from the sad iron.

A switch 17 is mounted upon a projecting portion 18 of the casing of the stand. This switch is of conventional design and for this reason, the details will not be given. A cable 19 connects with the switch, and at its free end is provided with a socket section 20 adapted to be plugged 40 into a wall socket of an electrical circuit. The switch 12 is controlled with a handle 21 by which it may be turned "on" or "off". The leads 22 from the switch connect with stationary resilient contacts 23 mounted upon the insulation block 45 13. These stationary contacts 23 house the movable contacts 14. The movable contacts 14 are provided with heads adapted to engage against the resilient contacts 23 in such a fashion that they are normally urged into downward position. 50 A cover 12^a is mounted upon the lugs 12 and extends over and covers the contacts 23 and associated electrical parts.

The insulation block is adjustably mounted upon the overhanging lugs 12. The adjustable 55

mounting comprises several bolts 25 engaged through circular openings in the lugs and through bayonet openings 26 in the block 13. The arrangement is such that the block maintains its position frictionally, but may be moved first longitudinally and then transversely to a position in which the contacts 14 no longer connect with the contacts 15 of the tail of the sad iron. With this arrangement it is possible to use the sad iron without the electrical facilities, in the event that the sad iron is heated with a gas burner or other foreign device. The feature of the arrangement is that the operation of the switch 17 is not depended upon to disconnect the circuit, so that in the event of damage or other spoiling of the switch, the sad iron stand may be used without danger of short circuiting.

A sad iron 27 is adapted to be used in conjunction with the stand. This sad iron is of a size so as to smartly set within the flanges 11 and to rest upon the support wall 10. The sad iron is provided with a conventional handle 28 having a thumb rest 29. The tail 16 is attached upon the rear of the sad iron and supports the contacts 15. These contacts are mounted in insulation material 30 supported upon the tail 16. The electrical circuit of the sad iron will not be given in this specification since it forms no part of this invention. It is sufficient to state that the contacts 15 are connected with a coil within the sad iron in a conventional manner so that when an electrical circuit is connected with the contacts 15 the sad iron will become heated.

A lip piece 31 is attached upon the front edge of the insulation block 13 and depends in such a fashion that the contacts 14 are shielded against accidental "touching" or short circuiting. The support wall 10 is formed with a rear opening 32 so that the contacts 14 are accessible through the bottom of the stand. The sad iron is of such size that in its operative position on the stand the tail 16 extends beneath the lip 31 and into a position in which the contacts 15 and 14 engage each other, provided the insulation block 13 is in its operative position.

A removable pin 33 is engaged through aligned openings in the sides of the cams 11^a of the flanges, and an opening through the sad iron (see Fig. 3), so that the sad iron may be locked upon the stand. The purpose of this arrangement is to connect the parts as a unit when they are stored away. For the operation of the device it is necessary that the pin 33 be removed.

The operation of the device consists in opening the switch 17 so that there is a circuit to the contacts 15. The iron 27 then becomes heated. It may be removed from the stand and used, and when rested upon the stand, because of the flanges 11 and the cam portions 11^a it will automatically seek its proper position to again close the circuit and so again, become further heated. It is necessary that the rear of the sad iron be placed first upon the support wall 10, with the front tip resting upon the cam portions 11^a, and then when the iron is released it will automatically slip rearwards so that the tail portion engages beneath the block 13.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I

claim as new, and desire to secure by United States Letters Patent is:—

1. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand.

2. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, and a switch mounted upon said casing and having flexible leads connected with said contacts.

3. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, and a switch mounted upon said casing and having flexible leads connected with said contacts, said casing having said flanges extended below said horizontal wall forming a hollow area beneath the support wall.

4. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, and a switch mounted upon said casing and having flexible leads connected with said contacts, said cam projections having aligned pin openings, and a locking pin adapted to engage through

said openings and through a passage in the sad iron for locking the sad iron on the stand when desired.

5. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, and a switch mounted upon said casing and having flexible leads connected with said contacts, said insulation block being formed with bayonet openings, bolts extended through said bayonet openings and through circular openings in said overhanging lugs, whereby said insulation block may be moved to a position in which said contacts do not engage each other.

6. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, and a switch mounted upon said casing and having flexible leads connected with said contacts, and a lip mounted upon the front edge of said insula-

tion block and depending to shield said contacts.

7. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, said resiliently supported contacts comprising stationary contact sections with resilient portions, and movable contact sections slidably arranged to engage the resilient sections and be forced into their lowered positions.

8. A sad iron stand for a sad iron having a tail with a pair of spaced contacts on its top, a casing having a horizontal sad iron support wall pointed at the front end and straight at the rear end, a flange surrounding the sides and pointed front of said wall, cam portions from the pointed portions of said flange for guiding said sad iron into proper position on the horizontal wall, a pair of spaced overhanging lugs projecting from the rear of said casing, an insulation block on the bottom and across said lugs, and resiliently supported contacts depending from the insulation block and adapted to automatically contact said spaced contacts on the tail of the sad iron when the sad iron is placed on said stand, said resiliently supported contacts comprising stationary contact sections with resilient portions, and movable contact sections slidably arranged to engage the resilient sections and be forced into their lowered positions, said flexible leads being connected with the stationary sections of said contacts.

WILLIAM EDELMAN.
